UNITED STATES PATENT OFFICE.

SOSTHENE ROBICHAUX, OF SARATOGA, TEXAS, ASSIGNEE OF ONE-HALF TO A. W. ROARK, OF HARDIN COUNTY, TEXAS.

BIT-CLEANER.

1,331,126.

Specification of Letters Patent.

Patented Feb. 17, 1920.

Application filed October 21, 1918. Serial No. 259,115.

To all whom it may concern:

Be it known that I, SOSTHENE ROBICHAUX, a citizen of the United States, residing at Saratoga, in the county of Hardin and State of Texas, have invented certain new and useful Improvements in Bit-Cleaners, of which the following is a specification.

This invention relates to new and useful improvements in a bit cleaner.

10 The object of the invention is to provide a device of the character described, which is designed for the purpose of cleaning bits used in drilling wells. In drilling wells, a drill stem is commonly employed which is 15 rotated by means of a rotary, from the ground surface, and to the lower end of this stem, a drill bit is attached. In drilling, certain formations through which the bit passes have a tendency to adhere to the bit, 20 and obstruct the drilling process. It is the object of this invention to provide an attachment which will automatically clean the bit, and remove the adhering formation, without the necessity of withdrawing the bit 25 to clean the same.

Another object of the invention is to provide an attachment of the character described, which will be automatically operated by the water which is forced down 30 through the drill stem to the point of the bit, to carry away the cuttings.

Another feature of the invention resides in the provision of a device of the character described, which is simple in construction, 35 and operation, and which may be readily applied to the drill stem.

With the above and other objects in view, the invention has particular relation to certain novel features of construction, operation 40 and arrangement of parts, an example of which is given in this specification and illustrated in the accompanying drawings, wherein:

Figure 1, is a vertical sectional view of 45 the upper part of the device, showing the operative mechanism.

Fig. 2, is a vertical sectional view of the lower end of the stem, showing the bit attached thereto, and the cleaning blades.

50 Fig. 3, is a vertical sectional view of the upper part of the device, taken at right angles to the view shown in Fig. 1.

Fig. 4, is a vertical sectional view of the lower part of the stem taken at right angles 55 to the view shown in Fig. 2.

Fig. 5, is a transverse sectional view taken on the line 5—5 of Fig. 1.

Fig. 6, is a transverse sectional view taken on the line 6—6 of Fig. 1.

Fig. 7, is a transverse sectional view taken 60 on the line 7—7 of Fig. 1.

Fig. 8, is a transverse sectional view taken on the line 8—8 of Fig. 1, and

Fig. 9, is a bottom view of the device.

Referring now more particularly to the 65 drawings, wherein like numerals of reference designate similar parts in each of the figures, the numeral 1, refers to a drill stem, the lower end of which is formed of a short tubular section 2, which is connected to the 70 stem by means of a collar 3. Within the upper end of the section 2, is a small turbine 4, which has the vertical drive shaft 5 connected thereto. This drive shaft has a bearing in the stuffing box 6, which is carried by 75 the transverse partition 7, of the section 2, and the lower end of this shaft has a bevel gear 8, fixed thereon, which is in mesh with a corresponding bevel gear 9, fixed on the transverse shaft 10. This last mentioned 80 shaft is operatively connected with and drives the crank shaft 11 through an intermediate train of gears 12. The crank shaft has a wrist pin 13, and a connecting rod 14 is provided, one end of which is pivoted to 85 the wrist pin 13, and the other end of which is pivoted to a cross head 15, which reciprocates within the section 2. The lower end of the section 2, is closed by means of the partition 16, and the mechanism between the 90 partitions 7 and 16, thus operates in a closed chamber, which is filled with oil, whereby the mechanism therein is lubricated. The partition 16 has a stuffing box 17, through which the rod 18 operates. The upper end 95 of this rod has a resilient cushion 19, against which it operates, and is provided for a purpose hereinafter to be explained.

To the lower end of the section 2, a nipple 20 is attached by means of the collar 21, and 100 the lower end of this nipple has a collar 22, to which the drill bit 23 is attached. The lower end of the collar 22 is internally threaded, and the drill bit has an externally threaded shank which is screwed thereon, 105 thus forming a means of attaching the bit 23 to the collar 22. A U-shaped member is provided, having the arms 24, 24. This member is attached to the lower end of the rod 18, and its arms extend through oppos- 110

ing vertical grooves 25, 25, in the threaded end of the collar 22, and the lower ends of these respective arms have the cleaning blades 26, 26, secured thereto, which fit 5 against opposing sides of the bit, and are reciprocated up and down to clean off said bit during the drilling process. The lower ends of these arms are connected by means of a transverse pin 27, which extends 10 through a vertical slot 28, cut through the bit.

In drilling, water is forced through the drill stem, and this water passes through the pipes 29, 29, whose respective ends are anchored in the partitions 7 and 16, and thence passes on down through the water 15 passageways 30, 30, of the bit, and thus reaches the point of the bit to carry away the cuttings. This water is forced through 20 the stem under pressure, and operates to rotate the turbine 4. This rotation is transmitted through the shaft 5, and the pinions 8 and 9, and the train of gears 12, to the crank shaft 11, which, in turn, reciprocates 25 the cross head 13 through the connecting rod 14, thus operating through the rod 18, and the arms 24, 24, to reciprocate the scraper blades 26, 26, for cleaning the bit. In case, a rock or hard stratum is encountered, 30 against which the blades 26, 26, contact, the yieldable seat 19 is compressed, thus permitting said blades to yield in order to prevent the breaking of the same.

The entire device may be readily removed 35 by unscrewing the section 2 from the collar 3, and an ordinary section of stem and bit may be substituted therefor when the formation is such as not to demand the use of the attachment herein described.

40 What I claim is:

1. A device of the character described, including a drill stem, having a bit attached to the lower end thereof, scraper blades carried by the bit, and means carried by the 45 stem for reciprocating said blades.

2. A device of the character described, including a drill stem, a bit carried by the

lower end thereof, reciprocating members carried by the bit and provided for freeing the bit from earth adhering thereto, and a 50 mechanism carried by the stem for automatically reciprocating said members.

3. A device of the character described, including a drill stem, a bit carried by the lower end thereof, reciprocating members 55 carried by the bit, and a mechanism adapted to be operated by the fluid passing through the said stem to reciprocate said members.

4. A device of the character described, including a drill stem, a bit carried by the 60 lower end thereof, reciprocating scraper blades carried by the bit, a turbine within the stem, and provided to be operated by the fluid passing under pressure through said stem, and a mechanism actuated by said turbine, and operatively connected with said blades and reciprocating the blades.

5. A device of the character described, including a tubular section adapted to be secured to the lower end of a drill stem, a 70 drill bit attached to the lower end of said member, scrapers carried by the bit, a mechanism within said section, operatively connected to said scrapers and actuating the same.

6. A device of the character described, including a tubular section adapted to be attached to the lower end of a drill stem, a drill bit attached to the lower end of said section, reciprocating scraper blades carried 80 by said bit, a turbine within said section, a mechanism operated by said turbine and operatively connected to said scraper blades through which the rotation of the turbine is effective to impart reciprocating movement to said scraper blades.

In testimony whereof I have signed my name to this specification in the presence of two subscribing witnesses.

SOSTHENE ROBICHAUX.
